UNITED STATES PATENT OFFICE

109,322

DESIGN FOR A HAND MAGNIFYING READING GLASS OR SIMILAR ARTICLE

Walter T. Hummel, Nuremberg-Bayern, Germany

Application March 14, 1938, Serial No. 75,791

Term of patent 7 years

To all whom it may concern:

Be it known that Walter Th. Hummel, a citizen of the Republic of Germany and resident of Nuremberg-Bayern, Germany, has invented a new, original, and ornamental Design for a Hand Magnifying Reading Glass or Similar Article, of which the following is a specification, reference being had to the accompanying drawing, forming part thereof, in which,

Fig. 1 is a front elevational view of a hand magnifying reading glass showing my new design, and

Figs. 2 and 3 are side elevational and bottom plan views, respectively, thereof.

I claim:

The ornamental design for a hand magnifying reading glass or similar article, as shown.

WALTER TH. HUMMEL.
